UNITED STATES PATENT OFFICE.

FREDERICK C. SIMMONS, OF HIGHLAND PARK, PENNSYLVANIA, ASSIGNOR TO
PIONEER SUSPENDER COMPANY, A CORPORATION OF PENNSYLVANIA.

METHOD AND MEANS OF BEVELING.

Application filed August 22, 1922. Serial No. 583,461.

To all whom it may concern:

Be it known that I, FREDERICK C. SIMMONS, a citizen of the United States, residing at Highland Park, in the county of Delaware, State of Pennsylvania, have invented, 5 aware, a new and useful Method and Means of Beveling, of which the following is a specification.

The invention relates to improvements in beveling. The object is to provide improved method and means for cutting bevels on the edges of strips or bands of leather or the like. The invention is especially applicable to cutting bevels on the side margins of 10 leather strips in the process of making belts for personal wear. The object is to give a rounded formation to its side edges which greatly improves the appearance of the belt when finished.

20 The present practice is to take the strips of leather which have been cut to the approximate width and length of the finished belt and with a very sharp knife shave off by hand the corners, one at a time, of said 25 margins. This is an expensive operation, since it requires a skillful operator to do the work properly and the output per hour is relatively small.

By the present invention, the strips are 30 beveled, as to their four marginal corners, simultaneously and with extreme accuracy, and with an output enormously increased over that of the hand operation.

35 Referring to the drawings, which illustrate, merely by way of example, suitable means for effecting the invention:—

Fig. 1 is a front elevation.

Fig. 2 is a right hand side elevation.

Fig. 3 is a left hand side elevation.

40 Fig. 4 is a plan view.

Fig. 5 is a vertical section on line 5, 5 of Fig. 4.

Fig. 6 is a vertical section on line 6, 6 of Fig. 5, on an enlarged scale.

45 Fig. 6^a is a fragmentary section on an enlarged scale.

Fig. 7 is a view in perspective of a roller supporting block.

50 Fig. 8 is a plan view of a bevel cutting or shaving element and associated mechanism.

Fig. 9 is a side elevation of same.

Fig. 10 is a front elevation of same.

Fig. 11 is an inside view of same in perspective.

55 Fig. 12 is an inside elevation of same.

Figs. 13, 14 and 15 are views in elevation, of the elements or members forming the angular way with the slot having the knife edge margins.

Fig. 16 is a cross-section of the strip after 60 being operated upon.

Similar numerals refer to similar parts throughout the several views.

Upon the table 21 is mounted the housing structure 22 in which are provided the bearings for the flanged wheels 23, 24, 25, 26, 27 and 28. The bearings are comprised in the adjustable blocks arranged in pairs, one of each pair being spring controlled so that the three pairs of wheels cooperate as to their 65 peripheries in a substantially common plane to carry the strip of material through the machine. The spring controlled strippers 29 are provided to prevent the strip of material from leaving its proper path of travel and following a wheel periphery. The three pairs of wheels 23 to 28 inclusive are driven by the motor 30 through the chains and sprockets as clearly shown. A tightening device is provided for the chain on one side 70 of the machine, as at 31 in Fig. 2, and for the chain on the other side of the machine, as at 32 in Fig. 3. A tightening device 34 is provided for the belt 35 connecting the motor to the fly-wheel 36. This device is 75 controlled by the spring 37, the tension of which is adjusted by the turn-buckle 38, see Figs. 2 and 3.

Suitably arranged in the path of travel of the strip are provided means for cutting or shaving away the upper and lower corners of the side margins of the strip of material, as it is carried through the machine.

These shaving devices are arranged in 90 pairs, one pair 40 and 41, in the present example, flanking the strip and adapted to cut the upper side marginal corners. The pair 42 and 43 flank the strip and are arranged to cut the lower side marginal corners. The pair comprising 40 and 41 are arranged in 95 advance of the pair 42 and 43.

As these shaving devices are all substantially the same in construction and operation, a detailed description of one such device and its associated mechanism, will make 100 clear the construction and operation of all the shaving devices.

Secured to the housing structure 22 on each side, near the adjacent peripheries of 105 wheels 23 and 24, is a structure such as is 110

- shown in Figs. 6 and 8 to 12 inclusive. This structure comprises the bracket 44, to which are secured the plates or elements 45 and 46, one at a right angle to the other. These two plates are beveled in the same plane as at 47, see Fig. 6^a. The adjacent edges of the bevel formation of 45 and 46 are in the form of sharp knife edges spaced apart leaving a slot 48.
- 10 The lower periphery of wheel 23 is in horizontal alinement with the inner under side of plate 45. To the inner side of bracket 44 is secured the roller 49; the upper periphery of this roller is in horizontal alinement with the upper periphery of wheel 24. It will thus be seen that the two wheels 23 and 24 and the elements 45, 46 and 49 of the flanking structures form together a rectangular passage of substantially the same cross-section dimensions of the strip 54, which is to be operated upon. The inner vertical surfaces of the plates 46 are spaced apart the exact width of the strip, so that the upper side marginal corners of the strip 54 will project through the slots 48. The wheels 23 and 24 exert a spring pressure on the strip, and, being positively rotated, cause the travel of the strip 54 through the passage formed therefor as above described. The roller 49 is mounted on arm 51, pivoted at 52 to bracket 44. The arm 51 is controlled by the spring 53 to cause a pressure of roller 49 on the strip 54. This insures the positive projection of the upper marginal corner of the strip 54 through the slot 48 and the effective pressure of the adjacent parts of said strip against the knife edge margins of the slot, as the strip travels through the passage.
- 40 Properly secured to the bracket 44 is the knife or planing blade 55. This blade is secured in place preferably by means of the plate 56 and securing screws. The plate 56 is provided with the pressure tongue 57 which extends over the blade 55 to near its cutting edge. The cutting edge of blade 55 lies against the beveled surface 47 and at an acute angle to the line of travel of said marginal corner of the strip 54.
- 50 In operation, as the strip of material 54 is fed in between the wheels 23 and 24 in the direction of the arrow in Fig. 5, the upper marginal corners of the strip are pushed with substantial pressure into the slot 48 with the adjacent portions of the strip firmly pressed against the knife edge margins of the slot 48. The cutting edge of the shaving blade 55, which lies upon the bevel 47 is in substantially the same plane as that of said knife edge margins of slot 48, it follows that said projecting marginal corners are cleanly shaved from the strip 54 as it passes against said shaving knives 55. The knife edge of the shaving blade being preferably in tight pressure contact with the

knife-edge-margins of the slot, at the point of shaving, the cutting or shaving operation partakes somewhat of the nature of a shearing action, so that the cutting or shearing is positive up to the knife-edge-margins, which effectually prevents tearing or frizzling the material on the lines of cut.

After passing the pair of shaving knives flanking the wheels 23 and 24, the strip passes to the similar shaving knives flanking the wheels 25 and 26. These knives however operate upon the lower side marginal corners of the strip, before the same passes through the delivery wheels 27 and 28.

What I claim is:—

1. The method of beveling which consists in moving a strip of material so that a corner of its side margin shall project between two longitudinally extending knife edges and encounter a shearing blade lying transverse its line of travel and substantially in the plane of said longitudinally extending knife edges.

2. The method of beveling which consists in moving a strip of material so that a corner of its side margin shall project between two longitudinally extending knife edges and encounter a shearing blade lying transverse its line of travel and substantially in the plane of said longitudinally extending knife edges, and pressing the material against a knife edge at the point of engagement with the shearing edge.

3. The method of beveling which consists in moving a strip of material so that a corner of its side margin shall project between two longitudinally extending knife edges and encounter a shearing blade lying transverse its line of travel and substantially in the plane of said longitudinally extending knife edges, and pressing the material against the knife edges on the line of engagement with the shearing edges.

4. In a beveling device, the combination of means for moving a strip of material, means forming a confined passage therefor, corresponding in cross-section substantially with the cross-section of the strip, and provided with a corner slot having parallel knife edge margins, and a shearing blade positioned transverse the slot and close to the knife edge margins.

5. In a beveling device, the combination of means including cooperating pressure wheels for moving a strip of material, means forming a confined passage therefor, corresponding in cross-section substantially with the cross-section of the strip, and provided with a corner slot having parallel knife edge margins, and a shearing blade positioned transverse the slot and close to the knife edge margins.

6. In a beveling device, the combination of means for moving a strip of material, means forming a confined passage therefor,

corresponding in cross-section substantially with the cross-section of the strip, and provided with a corner slot having parallel knife edge margins, means for pressing the strip during its travel against the knife-edge margins, and a shearing blade positioned transverse the slot and close to the knife edge margins.

7. In a beveling device, the combination of means for moving a strip of material, means forming a confined passage therefor, corresponding in cross-section substantially with the cross-section of the strip, and provided with a corner slot having parallel knife edge margins, and a shearing blade having its cutting edge in engagement with said knife edge margins.

8. In a beveling device, the combination of means for moving a strip of material, means forming a passage therefor corresponding substantially to the cross-section of the strip, means forming a slot having margins in the walls of said passage into which a marginal corner of the strip shall project, and a cutter cooperating with said

margins for severing from the strip said projecting corner.

9. In a beveling device, the combination of means for moving a strip of material, means forming a passage therefor corresponding substantially to the cross-section of the strip, means forming a slot having knife-edge-margins in the walls of said passage into which a marginal corner of the strip shall project, and a cutter having its edge in substantially the same plane as that of the said knife-edge-margins, for severing from the strip said marginal corner.

10. In a beveling device, the combination of means for moving a strip of material, means forming a guide channel for said strip including a bracket element and removable elements secured thereto, having knife-edge margins spaced apart for the projection of a corner of the strip between the same, and a cutting device having a shearing edge in substantially the same plane as said knife-edge margins.

FREDERICK C. SIMMONS.
